UNITED STATES PATENT OFFICE.

WILLIAM DUBILIER, OF NEW ROCHELLE, NEW YORK, ASSIGNOR TO DUBILIER CONDENSER CORPORATION, OF NEW YORK, N. Y., A CORPORATION OF DELAWARE.

ELECTRICAL RESISTANCE.

Application filed March 26, 1926. Serial No. 96,098.

This invention relates to improvements in electrical resistances; especially resistances for radio apparatus.

An object of the invention is to provide 5 an electrical resistance, particularly a resistance of the type generally designated as a grid leak, with all the conductive parts thereof in permanent and efficient contact, so that the resistance will operate to the best 10 advantage, without impairing the action of the other radio appliances with which it must be connected.

The nature of the invention is set forth in the following description and drawings, 15 which illustrate the best form of my invention now known to me; but the disclosure is illustrative only, and I may vary the details of construction without departing from the principle of the invention or exceeding the 20 scope of the appended claims.

On the drawings, the view presented shows in section a grid leak resistance according to my invention.

The numeral 1 indicates a tube or sleeve 25 in which is a conductive resistance rod or element 2, which may be of insulation, such as glass for example, or any other suitable material, covered with india ink or a film or envelope of some other substance having 30 the properties required to give the rod low electric conductivity. The sleeve 1 has its extremities closed as usual by conductive caps 3. To unite the ends of the rod or stem 2 to the caps, so that the rod can be put 35 into an electric radio circuit, I may snugly wrap each end of the rod 2 in thin piece or sheet metal, such as tinfoil 4, which I then tightly encircle by a metallic spiral 5, such as a piece of spring or wire which binds the 40 tinfoil upon the rod 2. Then each extremity of the rod 2 is set in an embedment of solder 45 6, which fills and closes the ends of the sleeve 1. This solder 6 effectively connects and unites the ends of the rod 2 to the caps 3, and when conductors engage the caps 3, the resistance is put into circuit.

This method of forming the grid leak makes a permanent and secure union between the rod and the caps 3 that are the 50 terminals of the grid leak. Often in such a device a little looseness between the ends of the rod or resistance element 2 will give rise to noises in a radio set containing it, and the clearness of the reception is thus greatly 55 reduced. To avoid such looseness and pre-

vent such noises the wrapping of tinfoil, encircled by the spiral spring 5, on each end of the rod 2 serves perfectly, and gives a very firm and durable contact between the rod and the caps 3 through the solder 6. 60

A certain amount of wrinkling or crumpling inevitably takes place when the metal foil is placed about the resistance element 2 and this crumpling is still further accentuated when the wires 5 are spirally wound about the foil. These minute wrinkles have a cushioning effect and are sufficiently springy to prevent the development of any looseness. 65

In some instances, I may use a piece in 70 the shape of a strip of tinfoil 7, wrapped spirally on the end of the rod and held by the spring binding member 5 as indicated at the right of the tube 1. The construction of the grid leak may thus be slightly different at each end, as illustrated, or a rolled sheet 4, with spring 5, be used at both ends; or a spiral strip of tinfoil 7, with a spiral member 5 be used at both ends, as one may desire. 75

Having described my invention, what I believe to be new and desire to secure and protect by Letters Patent of the United States is:—

1. A resistance comprising an element 80 with a piece of thin metal wrapped on its end, a spiral elastic binding member therefor, and a conductive embedment for the end of said element with said metal and said binding member. 85

2. A resistance comprising an element of 90 low conductivity, and parts crumpled about the ends and elastic means in contact with said crumpled parts for providing a secure and efficient connection of said element with an electric circuit.

3. A resistance comprising an element of 95 low conductivity, a metal sheet of foil wrapped on one end thereof, a spiral yielding binding member for said sheet, and a conductive embedment for said end with 100 said sheet and said member.

4. A resistance comprising an element of 105 low conductivity, a strip of thin metal wound spirally on one end thereof, a spiral elastic binding member therefor, and a conductive embedment for said end with said strip and said member.

In testimony whereof I affix my signature.
WILLIAM DUBILIER.
